Henry Pulster,

By J. Stuart Freeman,
Attorney.

UNITED STATES PATENT OFFICE.

HENRY PULSTER, OF PHILADELPHIA, PENNSYLVANIA.

BINDER FOR TEXTILE MACHINERY.

Application filed January 25, 1928. Serial No. 248,824.

The object of the invention is to provide improvements in certain details of the construction and operation of textile machinery and more particularly in a type of machine used to knit tubes such as are used in the formation of certain kinds of stockings, socks, and the like.

In circular knitting machines, especially when several yarns of different size, color, or material are being used, the threads which are severed and not actually being worked at a given moment are constantly in danger of slipping, and in fact do often slip, free from the single binder heretofore employed, with the result that each machine requires constant tending, so-called press-offs and drop stitches occur, and the resulting tube can only be used in a finished article of "second" quality, or must be rejected altogether.

The object therefore is to provide an improvement in the mechanism which holds the ends of severed threads, and through which the threads of various sizes, colors, or materials are supplied to the needles. Also, in addition to the single spring-pressed liftable binder heretofore employed in contact with a yielding cushion or platen, a second such binder is provided in addition to a plurality of resilient or auxiliary fingers, which are constantly in engagement with the surface over which the threads pass, and at all times cooperate with each other and with the liftable binders, to positively prevent the escape of a single thread at any time from a position accessible to the needles.

A further object is to provide a beading or flange, which rises gradually from the surrounding surface of the thread support, and surrounds the peripheral edge portion of the cushion or platen to protect the latter and its connection with said surface, and prevent threads from entering beneath said platen, loosening a portion of its edge, and causing the threads to snag or catch thereon instead of entering freely beneath the liftable binders and a knife in proximity thereto.

With these and other objects in mind, the present invention comprises further details of construction and operation which are fully brought out in the following description,

when read in conjunction with the accompanying drawings, in which Fig. 1 is a top plan view of that portion of a knitting machine involving the present invention; Fig. 2 is an elevation of the same; Fig. 3 is a fragmentary elevation of the same showing the knife and liftable binders in raised position; and Fig. 4 is a section on the line 4—4 of Fig. 1.

The embodiment of the invention here illustrated comprises a suitable bracket 1 by which the device is attached in suitable manner to the frame of a knitting machine, said bracket comprising an upright portion 2, to the under side of which is secured a gear 3, adapted to mesh with and be rotated by another gear or circular rack (not shown). Upon said upright portion there is secured a disc 4, having an upwardly extending cylindrical flange 5, the radially outer surface 65 of which flange is a continuation of the corresponding surface of said disc, and said surface of cylindrical shape being provided with upwardly extending parallel spurs 6 between which needles (not shown) are adapted to 70 reciprocate.

Supported above the upper surface of the disc 4 by any suitable means is a disc 8, comprising a platform, the upper surface of which is hollowed out at one point 9 and 80 surrounded by an upwardly extending flange 10, which surrounds and incloses the edge portions of a yielding cushion or platen 11 made of pig skin or other suitable material, the outwardly directed surface of said flange 85 merging very gradually into the surrounding surface of said platform disc 8, so that a thread 12 passing laterally across said platform is raised in the vicinity of the hollowed out region 9 until it passes freely 90 over the edges of, and extends across, said platen 11.

The upwardly extending portion 2 of the bracket 1 is furthermore provided with a laterally extending arm 13, which terminates 95 outwardly in a second bracket 14 which extends upwardly beyond the level of the platform 8 and upon which is mounted a head 15 by any suitable means, such for instance as the spaced screws 16, said head comprising an 100

integral upward and lateral extension of the platform disc 8 through an integral connecting portion 17. The head 15 is provided with an angularly directed substantially vertically extending surface 18, to which a pair of independent liftable binders 19 are pivoted, said binders being lifted by means of any suitable spring 20, such for instance as the wire spring shown in Fig. 1, which at one end engages the pivotal support 21 of said binders and at its opposite end extends beneath the latter.

The head 15 is provided also with a second substantially vertically extending surface 22, to which is pivotally secured through a bolt 23 an arm 24, the free end portion 25 of which bears against the upper surface of the respective liftable binders 19, said arm 24 also supporting in pivotal engagement the upper bifurcated portion 26 of a depending knife blade 27, which is maintained in engagement with the edge 28 of a segmental cutaway portion of the platform disc 8, by means of any suitable type of spring 29 extending between said blade and the screw or bolt 23 or other fixed portion of the device.

In addition to the liftable binders 19, there is also secured to the surface 18 of the head 15 a lever 30 by means of a bolt 31, one end portion 32 of said lever being in normal engagement with a movable portion of the textile machine (not shown), while the opposite free end portion 33 of said lever is adapted to bear against the upper surface of the free end portion 25 of the arm 24 for a purpose hereinafter described. Also in addition to the liftable binders 19 there extend across and in yielding uniform contact with the upper surface of the platform disc 8 (held in place by the screw 7) a plurality of resilient fingers 35 or auxiliary binders 34, the outer free ends 36 of which are turned upwardly so as to assist in permitting threads of yarn to be quickly entered beneath them, while the opposite or fixed ends of said auxiliary binders are secured beneath the bolt 7 or other suitable means. Still furthermore, a thread guide 36 has a fixed end also secured beneath the bolt 7, while its angularly directed free end portion 37 extends outwardly beyond the limits 50 of the spurs 6 and throughout its length is in spaced relation with the platform disc 8, said guide being relatively stiffer than, and as its name implies merely designed to assist in guiding threads beneath, the yielding auxiliary binders 34.

In the operation of the device, several threads of yarn of differing size, color, material, et cetera, extend across the upper surface of the disc 8 beneath the auxiliary binders 34 and also beneath the liftable binders 19, being held by the latter in frictional contact with the corrugations 11 in the platen 11 and their freely extending ends having been previously sheared by the knife blade 27. During the operation of the knife mechanism,

the proper thread is caught by one of the spurs 6 and drawn into operating proximity with the needles (not shown in the drawings), the loop of said thread caught by the spur is rotated by the latter in the direction of the arrow 38, said thread finally being directed by the guide 36 beneath the auxiliary binders 34 and also beneath the liftable binders 19, the latter having been lifted by the spring 20 free from engagement with the platen 11, upon the lever head 33 having been released upwardly, it being obvious that the blade 27 has also risen with said liftable binders due to the downward pressure of the free end portion 39 of a laminated spring secured beneath the bolts or screws 16 in the head 15 upon the oppositely directed free end portion 40 of the arm 24. Practically immediately after the rise of said liftable binders 19 and the blade 27, the thread before mentioned passes beneath the former and is cut by the latter, the end of said thread extending across said platen being immediately caught by and held beneath said liftable binders which have descended under and by virtue of the action of the lever head 33 against the combined pressures of the springs 20 and 39, after which the thread cannot become loosened from contact with said platen until said liftable binders are again permitted to rise. Also after the liftable binders rise in each case, the auxiliary binders 34 continue to hold the thread against the platform disc 8 and prevent its accidental removal laterally therefrom.

Having thus described my invention, what I claim as new and desire to protect by Letters Patent of the United States is:

1. An attachment for textile machines, comprising a platform, a platen of relatively yielding material carried by said platform, a binder supported in pivotal relation with said platform and adapted to bear against said platen, and a beading surrounding said platen and gradually merging into the surface of said platform, to prevent threads from entering beneath and separating said platen from said platform.

2. An attachment for textile machines, comprising a platform, a platen of relatively yielding material carried by said platform, a binder supported in pivotal relation with said platform and adapted to bear against said platen, a beading surrounding said platen and gradually merging into the surface of said platform, to prevent threads from entering beneath and separating said platen from said platform, and an auxiliary binder fixed at one portion with relation to, and its free end portion adapted to bear yielding against, said platform.

3. An attachment for textile machines, comprising a platform, a platen of relatively yielding material carried by said platform, a beading surrounding said platform and op-

- erative to prevent threads from entering beneath and separating said platen from said platform, and a pair of independent binders pivotally mounted with respect to said platform and adapted to engage said platen. 4. An attachment for textile machines, comprising a platform, a platen of relatively yielding material carried by said platform, a beading surrounding said platform and operative to prevent threads from entering beneath and separating said platen from said platform, a pair of independent binders pivotally mounted with respect to said platform and adapted to engage said platen, and an auxiliary binder comprising a resilient member fixed at one end with respect to said platform and with its free end in yielding engagement with said platform. 5. An attachment for textile machines, comprising a platform, a platen of relatively yielding material carried by said platform, a beading surrounding said platform and operative to prevent threads from entering beneath and separating said platen from said platform, a pair of independent binders pivotally mounted with respect to said platform and adapted to engage said platen, and an auxiliary binder comprising a resilient member fixed at one end with respect to said platform and with its free end in yielding engagement with said platform; its free end being spaced from said platform and operative to guide threads under each binder. 6. An attachment for textile machines, comprising a platform, a platen of relatively yielding material carried by said platform, a beading surrounding said platform and operative to prevent threads from entering beneath and separating said platen from said platform, a pair of independent binders pivotally mounted with respect to said platform and adapted to engage said platen, and means to guide threads under said binders. 7. An attachment for textile machines, comprising a platform, a platen of relatively yielding material carried by said platform, a beading surrounding said platform and operative to prevent threads from entering beneath and separating said platen from said platform, a pair of independent binders pivotally mounted with respect to said platform and adapted to engage said platen, and an auxiliary binder comprising a resilient member fixed at one end with respect to said platform and with its free end in yielding engagement with said platform, said last-named binder being also operative as a means to guide threads beneath each of said binders. 8. An attachment for textile machines, comprising a platform, a platen of relatively yielding material carried by said platform, a beading surrounding said platform and operative to prevent threads from entering beneath and separating said platen from said platform, a pair of independent binders pivotally mounted with respect to said platform and adapted to engage said platen, and a pair of auxiliary binders comprising a resilient member having an intermediate portion fixed with respect to said platform, and its free end portions in normal yielding relation with said platform. 9. An attachment for textile machines, comprising a platform, a platen of relatively yielding material carried by said platform, a beading surrounding said platform and operative to prevent threads from entering beneath and separating said platen from said platform, a pair of independent binders pivotally mounted with respect to said platform and adapted to engage said platen, a pair of auxiliary binders comprising a resilient member having an intermediate portion fixed with respect to said platform, and its free end portions in normal yielding relation with said platform, and a guide member having one end fixed with respect to said platform and extending in substantially parallel and slightly spaced relation therewith.
- In testimony whereof I have affixed my signature.
